UNITED STATES PATENT OFFICE.

EMILY SLAUSON, OF RACINE, WISCONSIN.

HEEL-PROTECTOR FOR SHOES.

SPECIFICATION forming part of Letters Patent No. 628,188, dated July 4, 1899.

Application filed August 29, 1896. Serial No. 604,277. (No model.)

To all whom it may concern:

Be it known that I, EMILY SLAUSON, of Racine, in the county of Racine and State of Wisconsin, have invented a new and useful Improvement in Heel-Protectors for Shoes, of which the following is a description, reference being had to the accompanying drawings, which are a part of this specification.

My invention has relation to improvements in heel-protectors for foot-gear.

The object is to provide an improved arrangement and combination of an interior guard or protecting-strip at the heel of the shoe, so that rubbing or abrading of the heel experienced in walking is avoided, thereby saving not only the sock or stocking from wear, but the shoe-lining as well, and, furthermore, preventing the disagreeable blistering of the heel of the foot.

In the accompanying drawings, Figure 1 is an elevation of a shoe, showing a portion thereof broken away to illustrate the application of my invention to the interior thereof. Fig. 2 is a detail of the protecting-strip; and Fig. 3 is a similar view to Fig. 1, showing a slight modification in the protecting-strip.

Referring to the drawings, the numeral 4 indicates an ordinary form of lady's shoe. In combination with the shoe I provide a protecting-strip, advisedly of some soft material, such as ribbed wool and cotton. This material is indicated in the accompanying drawings by the numeral 5 and is represented with the ribs extending vertically. The strip 5 is designed to be arranged within the rear or heel portion of the shoe, the material being curved around the back of the shoe and then extended along opposite sides for a desired distance. It is attached at its upper edge to the shoe, and in order to offer as little obstruction as possible to the heel when the shoe is being put upon the foot this upper edge is passed beneath the top edge lining 6 of the shoe and secured between said lining and the main lining by stitches 7. The lower edge and the sides of the strip should be free and should extend to, or approximately to, the insole.

It is a well-known fact that in walking there is a constant rubbing or friction between the heel of the foot and the back of

the shoe, particularly at the part of the shoe where the counter joins the back, there being a slight inward bend at such point. This constant rubbing soon wears out the lining of the shoe as well as the heel of the stocking or sock and frequently causes a disagreeable blistering of the heel of the foot. All of these difficulties are effectually avoided by the use of my invention, as I provide a strip of material interposed between the heel of the foot and the back of the shoe, said material adapted to receive directly the rubbing action of the heel, and being left free at its lower edge and side edges it follows the movement of the heel of the foot, whereby no rubbing whatever directly on the heel is produced.

While, as previously stated, I prefer to form the strip of ribbed wool and cotton, yet I do not wish to be understood as limiting myself thereto, as any other desirable soft substance may be used—as, for instance, buckskin, which latter has been found by experience to secure good results. Where a material composed of ribbed wool and cotton is used, however, it is advisable to arrange such material so that the ribs will extend vertically. This prevents entirely wrinkling or curling up of the material when the heel is withdrawn from the shoe.

It will be noticed that in Figs. 1 and 2, which are intended to illustrate the material as composed of ribbed wool and cotton, the ribs are shown as vertical throughout the entire length of the strip. In the form illustrated in Fig. 3, which also represents a ribbed wool and cotton strip, the ribs terminate somewhat short of the upper edge of the material, leaving the upper portion of a plain stitch or unribbed, as indicated at 8. This plain portion is intended to be inserted beneath the lining 6 and to receive the stitches 7. The plain or unribbed portion being thinner than the main ribbed portion of the strip is better adapted to fit smoothly beneath the lining 6 and to thereby cause less bulge upon the interior of the shoe.

My protector may be applied to the shoe either during the process of making the shoe or after said shoe is completed. Where, however, the upper edge of the strip is stitched beneath the top edge lining 6, it is more con-

veniently applied during the process of making.

The invention is more particularly intended for use in connection with the more common machine-made shoes which are worn by the masses of the people rather than with the more expensive hand-made quality, as the former are made to fit the last, while the latter more accurately fit the foot of the wearer.

10. What I claim as my invention is—

In a heel-protector, the combination, with a shoe, of a strip of soft material applied to the interior of the shoe at the back thereof,

and extending around the sides of the shoe for a desired distance, the strip being secured 15 only at its upper edge to the shoe so as to leave the side edges and the lower edge of said strip free, thereby adapting the strip to follow the different movements of the heel of the foot.

In testimony whereof I affix my signature in presence of two witnesses.

EMILY SLAUSON.
